PC(57) **CLAIM**

The ornamental design for an indicator for elevator, as shown and described.

DESCRIPTION

FIG. 1. is a perspective view of the front, right, and top sides of an indicator for elevator as viewed from a front showing my new design;

FIG. 2. is a front view thereof;

FIG. 3. is a rear view thereof;

FIG. 4. is a right side view thereof; a left side view being a mirror image thereof;

FIG. 5. is a top plan view thereof; a bottom plan view being a mirror image thereof;

FIG. 6. is an enlarged end view of cutting part at 6-6 in FIG.

2 omitting the internal mechanism; and,

FIG. 7. is a reference view showing in use thereof.

The broken lines in FIG. 7 represent environment and forms no part of the claimed design.
